Inventor,

Benj. G. Devoe,

Ass't to Lima Fence Company,
B. C. Converse Atty.

UNITED STATES PATENT OFFICE.

BENJAMIN G. DEVOE, OF KENTON, ASSIGNOR TO THE LIMA IRON FENCE COMPANY, OF LIMA, OHIO.

IRON FENCE.

SPECIFICATION forming part of Letters Patent No. 271,196, dated January 23, 1883.

Application filed September 28, 1882. (No model.)

To all whom it may concern:

Be it known that I, BENJAMIN G. DEVOE, a citizen of the United States, residing at Kenton, in the county of Hardin and State of Ohio, have invented certain new and useful Improvements in Iron Fences; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention relates to improvements in iron fences having punched rails; and it consists, first, in the manner of securing the malleable ornament to the picket-rod; second, in the construction and arrangement of the bearing parts of the ornaments upon the rails, whereby the pickets and rails can be more easily adapted to inclined grades.

20 Figure 1 is a front elevation of two pickets connected by a portion of the upper rail of my improved iron fence. Fig. 2 is a vertical section of the picket through the rod and ornament, and a cross-section of the rail through which the rod extends. Fig. 3 is a top view of the rail and a cross-section of the picket-rod in the hole of the rail. Fig. 4 is a rear view of the ornament detached.

25 The object of my invention is to provide means for the adjustment of the rails and pickets by bearings extending from the ornaments of the latter and resting upon diagonally-opposite points of the rail upon either side of the picket-rod, for which purpose a channel-T form of rail is used by preference.

30 Another object of my invention is to permanently secure the ornament of the picket to the rod, so that the latter cannot be turned within the former, thereby retaining the ornament in place upon the rod, and making the fence stronger and more durable.

35 A is a portion of fence to which my improvements are applied, consisting of the two pickets *a*, connected by a piece of the upper rail, *c*. (Seen in Fig. 1.) A portion of the rail is broken out at the front, so as to show the position of

the picket and its relation to the rail through which it extends. 50

a' is the ornament, which has two rearward and downward extending loops, *d* and *e*, (the latter at its lower end,) which inclose the rod *b* above and below the rail. An angular projection, *f*, at the top of loop *e*, on the inside of the ornament, forms a bearing for the lower edge of the front flange, *g*, of the rail. Between this and the end of loop *d*, which rests upon the rear edge of the upper surface at the angle *c'*, the rail is supported. The hole *h* in the rail is made oblong, as seen in Fig. 3, to receive the picket and to allow of the adjustment of the rail thereon to inclined grades, as seen in the view Fig. 1. This part I do not claim as new, as oblong holes have been before used, though not in connection with the other parts heretofore described. The hole *h* is made through the main or body part connecting the front and rear flanges, and the picket-rod *b* extends through the loop *d*, (seen extending at an angle downward from the ornament at the middle part,) through the rail, and through loop *e* at the lower end of the ornament. The top of the ornament inclosing the rod is tubular, as seen in the figures, and on the rear side, near the top, there is an indentation, *i*, cast in it, the object of which is to allow of the thin metal at the bottom being set into the rod *b* by means of a taper round-ended punch indenting both ornament and rod together, as seen in Fig. 2. The rod used in this example is round, although a square rod may be substituted, the interior of the tubular portion and loops of the ornament being made to correspond. 75 80 85

The parallel dotted lines at the middle of rail *c* in Fig. 1 represent the body of the same. By reference to this figure it will be seen that while the rail is readily adjustable between the points *d* and *f* it is securely held from vertical displacement upon the picket-rod by these bearings, which rest directly upon it above and below at diagonally-opposite points. 90

I am aware that ornaments having loops above and below the rail, through which the rod of the picket extends, are not new, and I therefore do not claim them; but my device 95

differs materially in that the bearing points are formed upon the ornament, which pivot the rail between them, these points being diagonally opposite and resting on the outer surfaces of the rail.

5 I claim as my improvement—

1. In an iron fence having wrought rods and malleable ornaments, the means for securing the ornament to the picket-rod, which 10 consists in casting said ornament with an indentation therein, as described, and having the metal of the ornament indented or driven into the rod by a punch, substantially as set forth.

15 2. In an iron fence having a channel-T-shaped rail punched for the picket-rods, an ornament provided with two loops—one above and one below the rail—each inclosing the picket-rod and extending rearward and downward in parallel lines, the upper loop resting 20 upon the top surface of the rail behind the picket-rod, and operating in connection with an angular bearing which supports the front flange of said rail, as a means for allowing the 25 adjustment of the latter to grade, substantially as set forth.

3. In an iron fence having punched rails and malleable ornaments, a picket ornament provided with an angular bearing to support the front flange, and a downward and rearward 30 extending loop inclosing the rod above the rail, and resting upon the rear upper surface of the latter behind the rod, whereby an upper and lower bearing of said rail is secured at diagonally opposite points, substantially as 35 set forth.

4. In an iron fence having punched rails and malleable ornaments, a picket ornament provided with diagonally-opposite bearings for the upper and under surface of the rail, which 40 latter is adjustable thereon, and having its inclosing-loops extending rearward and downward in the same direction, substantially as set forth.

In testimony whereof I affix my signature in 45 presence of two witnesses.

BENJAMIN G. DEVOE.
